UNITED STATES PATENT OFFICE.

WILLIAM C. MEYER, OF BOSTON, MASSACHUSETTS, ASSIGNOR TO UNITED SHOE MACHINERY COMPANY, OF PATERSON, NEW JERSEY, A CORPORATION OF NEW JERSEY.

MACHINE FOR MOLDING OR BENDING SHOE-SOLES.

1,110,637.

Specification of Letters Patent. Patented Sept. 15, 1914.

Application filed December 10, 1909. Serial No. 532,307.

To all whom it may concern:

Be it known that I, WILLIAM C. MEYER, a citizen of the United States, residing at Boston, in the county of Suffolk and State 5 of Massachusetts, have invented certain new and useful Improvements in Machines for Molding or Bending Shoe-Soles; and I do hereby declare the following to be a full, clear, and exact description of the invention, 10 such as will enable others skilled in the art to which it appertains to make and use the same.

Prior to the operation of lasting a turn shoe it is customary to bend down the margin of the sole in order that it may be more conveniently lasted and sewed. This operation is commonly performed by a machine provided with two rollers which are rotated to feed the work, and which engage the opposite sides of the sole margin, these rollers being suitably formed to mold or bend the material of the sole to the required form.

The present invention relates to machines of the type above described, and the object 25 of the invention is to improve the structure, arrangement and mode of operation of certain parts of such a machine.

With the above object in view, a feature 30 of the invention relates to improved provisions for adjustment of certain parts of the machine.

Other features of the invention consist in certain improved constructions, combinations and arrangements of parts hereinafter described and claimed, the advantages of which will be obvious to those skilled in the art from the following description.

In the accompanying drawings, which illustrate the preferred embodiment of my invention, Figure 1 is a side elevation of a turn sole molding or bending machine; Fig. 2 is a front elevation of the machine; Fig. 3 is a rear elevation of the machine; Fig. 4 is a sectional elevation of the operative instrumentalities of the machine; Fig. 5 is an enlarged detail view in front elevation, showing the upper roll and the work guide.

The illustrated embodiment of the invention is provided with an upper tool or roll 50 comprising three parts. The part 1 of this tool is provided with teeth or corrugations by which the feeding of the work is insured. The part 6 is cylindrical, and this part and the part 1 constitute together a generally

cylindrical portion adapted to engage the upper surface of the body portion of the sole margin. The third part 3 of the upper roll is in the form of a flange or disk having a beveled and roughened surface adapted to engage the upper surface of the sole and to bend down or mold the extreme marginal portion of the sole in the usual manner. The upper roll is carried by a power shaft 4, being mounted on a screw 5 threaded into the forward end of the shaft. This screw, 65 together with two adjusting nuts 7 which are threaded on the end of the shaft, constitute means for adjusting the upper roll axially, this adjustment being accomplished by rotating the nuts or the shaft until the 70 roll is in proper position, and then tightening the screw 5 to secure the parts of the roll together in adjusted position. The shaft 4 is journaled in the frame 8 of the machine, and is provided with a fast pulley 9 and a 75 loose pulley 10, together with a belt shipper 11, by which the machine may be started and stopped when run by power. The machine is also provided with a hand crank 13 connected with the shaft 4 by gears 12, so 80 that the machine may be actuated by hand if desired. The lower roll 2 is of a form common in machines of this type, and it has a rounded form providing surfaces adapted to coöperate both with the cylindrical portion of the upper roll, to grip the body of the sole, and with the part 3 of the upper roll, to grip the bent margin of the sole. The lower roll is mounted upon an inclined shaft 14 which turns in a casing 15 85 pivotally mounted at 16 on the frame of the machine. To permit the lower roll to accommodate itself to variations in thickness in the work, and also to facilitate the introduction of the work between the rolls, provision is made for pivotal movement of the casing 15, by which the roll 2 is moved in a direction transverse to its axis and toward and from the upper roll. To this end a rod 18 is pivoted at 17 to the front of the casing 100 15, and this rod passes loosely through a lug 19 extending from the frame of the machine. A compression spring 20 engages the lug 19 and an adjustable nut 21 on the rod 18, and this spring tends constantly to hold 105 the roll 2 up against the work.

To provide for the easy introduction of the work between the rolls, a treadle me-

chanism is provided for drawing the roll 2 down and away from the upper roll. A bell-crank lever 22 is pivoted at 24 on the frame 8, and the short arm of this lever engages a nut on the rod 18. The long arm of the lever is connected by a rod 25 with a treadle 26.

To prevent contact between the rolls when there is no work in the machine, a stop 10 screw 27 is threaded in the lever 22 in position to engage a stop 28 on the frame 8, so as to limit the upward movement of the lever and of the roll 2. The stop screw is adjustable so as to accommodate its operation to rolls of different diameters.

The upper roll alone may be actuated, but it is preferred to actuate both rolls in unison, and to this end bevel gears 35 and 36 are mounted upon the shafts 14 and 4, these 20 gears being arranged to mesh so near to the pivot 16 that their operation is not interfered with by the pivotal movements of the casing 15.

In addition to the operative instrumentalities hereinbefore described, the machine is provided with a work guide 29 arranged to engage the edge of the sole. This guide is mounted on a stem 30 which is carried in a sleeve 31 and is adjustably secured by a set screw 32. This arrangement permits the work guide to be adjusted axially with respect to the upper roll. The sleeve 31 is carried on a slide 33 which is vertically adjustable on the frame 8, and is fixed in position by a screw 34 engaging an elongated opening in the slide. This construction permits the guide to be adjusted transversely with respect to the upper roll. The two adjustments of the work guide together adapt it to coöperate with rolls of different forms and sizes, and also permit the work guide to be adjusted to compensate for the axial adjustment of the upper roll hereinbefore described. By the axial adjustment of the 40 upper roll, in combination with the transverse adjustment of the lower roll, the machine may be adjusted to operate upon a sole having a body of any thickness and a margin of the same or any other thickness, and the machine is therefore adapted for use 50 on a wider variety of work than a machine constructed without such provision for adjustment.

My invention is not limited to the construction hereinbefore described and illustrated in the accompanying drawings, but may be embodied in other forms within the nature of the invention and the scope of the following claims.

Having set forth the nature and object 60 of the invention, and specifically described one form of machine in which it may be embodied, what I claim is—

1. A machine for molding or bending shoe soles, having, in combination, two coöperat-

ing rolls constructed and arranged to bend the margin of the sole away from the plane of the body of the sole, means for obtaining an adjustment of one of the rolls axially, and a work guide for determining the distance at which the sole is bent from the edge of the sole arranged between the rolls to engage the edge of the sole and adjustable axially and transversely with respect to said last mentioned roll, substantially as described.

2. A machine for molding or bending shoe soles comprising a roll, a shaft upon which said roll is mounted, with provision for axial adjustment of said roll, including a screw 80 passing through said roll and threaded into the forward end of said shaft, and adjusting nuts threaded on the forward end of said shaft, substantially as described.

3. A machine for molding or bending shoe soles, having, in combination, two coöperating rolls constructed and arranged to bend the marginal portion of the sole away from the plane of the body of the sole, a shaft upon which one of said rolls is mounted 90 with provision for axial adjustment of the roll, a second shaft upon which the other of said rolls is mounted, means for supporting said shafts at an inclination to each other, and a work guide for determining the 95 distance at which the sole is bent from the edge of the sole arranged between the rolls to engage the edge of the sole and adjustable axially of said first roll and transversely with relation to both of said rolls, 100 substantially as described.

4. A machine for molding or bending shoe soles, having, in combination, two coöperating rolls constructed and arranged to bend the marginal portion of the sole from the 105 plane of the body of the sole, a shaft upon which one of said rolls is mounted, a second shaft upon which the other of said rolls is mounted arranged below and at an angle to said first shaft, a casing pivoted to the frame 110 and supporting said second shaft, a gear carried by said first shaft, a second gear carried by said second shaft meshing with said first gear and arranged adjacent the pivotal point of said casing and between said point 115 and the second roll, means acting on said casing to press the second roll yieldingly toward said first roll, a lever connected with said casing, a treadle, and connections from the treadle to said lever whereby the rolls 120 may be separated manually to introduce the work therebetween, substantially as described.

5. A machine for molding or bending shoe soles comprising two coöperating rolls, 125 shafts on which said rolls are respectively mounted, a work guide adjustable axially of one of said rolls and transversely with relation to both of said rolls, means to adjust said guide including a sleeve in which said 130

guide is adjustably mounted, and an adjustable slide on which said sleeve is carried, substantially as described.

6. A machine for molding or bending shoe soles having, in combination, a driving shaft, a molding roll mounted on said shaft, a fast and a loose pulley carried by said shaft intermediate the bearings thereof, a second shaft arranged below and at an angle 10 to said first shaft, a second molding roll carried by said second shaft and coöperating with said first roll to bend the marginal portion of the sole away from the plane of the sole body, a pivoted casing supporting said second shaft, a bevel gear carried by said first shaft, a second bevel gear carried by said second shaft, meshing with said first gear and arranged adjacent the pivotal point of said casing and between the said point and the 15 second roll, a resilient member acting on said casing to press said second roll yieldingly toward said first roll, a treadle and connections therefrom to said casing for moving said casing on its pivot to separate 20 said molding rolls to permit the introduction and removal of the work, substantially as described.
7. A machine for molding or bending shoe soles, having, in combination, a molding roll having a sole margin engaging portion, a second roll having a sole body engaging portion arranged at an angle to the sole margin engaging portion of said first roll and co-operating therewith to bend the marginal 25

portion of the sole away from the plane of 35 the sole body, means for obtaining an adjustment of one of said rolls axially, and a work guide for determining the distance of the point at which the sole is bent from the edge of the sole arranged between the rolls 40 to engage the edge of the sole and adjustable axially and transversely with respect to said last mentioned roll, substantially as described.

8. A machine for molding or bending shoe soles, having, in combination, two coöperating rolls each provided with a sole body engaging portion and a sole margin engaging portion arranged at an angle with the sole body engaging portion for bending the marginal portion of the sole away from the plane of the sole body, means for obtaining a relative adjustment of the rolls to vary independently 50 the distance between the sole body engaging portions and the sole margin engaging portions of the rolls, and a work guide for determining the distance at which the sole is bent from the edge of the sole arranged between the rolls, and mounted 55 for adjustment axially with relation to one of the rolls and transversely with relation to both of the rolls, substantially as described.
